(57) **CLAIM**

The ornamental design for a tile, as shown and described.

DESCRIPTION

FIG. 1 is a top plan view of a first embodiment of a tile; FIG. 2 is a bottom plan view of the first embodiment of the tile of FIG. 1;

FIG. 3 is a front elevational view of the first embodiment of the tile of FIG. 1;

FIG. 4 is a rear elevational view of the first embodiment of the tile of FIG. 1;

FIG. 5 is a left side elevational view of the first embodiment of the tile of FIG. 1;

FIG. 6 is a right side elevational view of the first embodiment of the tile of FIG. 1;

FIG. 7 is a top plan view of a second embodiment of a tile; FIG. 8 is a bottom plan view of the second embodiment of the tile of FIG. 7;

FIG. 9 is a front elevational view of the second embodiment of the tile of FIG. 7;

FIG. 10 is a rear elevational view of the second embodiment of the tile of FIG. 7;

FIG. 11 is a left side elevational view of the second embodiment of the tile of FIG. 7;

FIG. 12 is a right side elevational view of the second embodiment of the tile of FIG. 7

FIG. 13 is a top plan view of a third embodiment of a tile; FIG. 14 is a bottom plan view of the third embodiment of the tile of FIG. 13;

FIG. 15 is a front elevational view of the third embodiment of the tile of FIG. 13;

FIG. 16 is a rear elevational view of the third embodiment of the tile of FIG. 13;

FIG. 17 is a left side elevational view of the third embodiment of the tile of FIG. 13; and,

FIG. 18 is a right side elevational view of the third embodiment of the tile of FIG. 13.

Gray scale shading in the drawings represents contrast in appearance.
